DESIGN FOR NARROW ELASTIC TAPE

John V. Moore, Pawtucket, R. I., assignor to Moore Fabric Company, Pawtucket, R. I., a corporation of Rhode Island

Application July 16, 1934, Serial No. 52,595

Term of patent 7 years

To all whom it may concern:

Be it known that I, JOHN V. MOORE, a citizen of the United States, residing at Pawtucket, in the county of Providence and State of Rhode Island, have invented a new, original, and ornamental Design for Narrow Elastic Tape, of which the following is a specification, reference being had to the accompanying drawing, forming part thereof.

Fig. 1 is plan view of a piece of narrow elastic tape, showing my new design;

Fig. 2 is a side view showing the tape, and
Fig. 3 is a section on the line 3—3 in Fig. 2.

I claim:

The ornamental design for narrow elastic tape as shown.

JOHN V. MOORE.
